UNITED STATES PATENT OFFICE

ILLÉS ZAYMUSZ, OF BUDAPEST, HUNGARY

THRASHING MACHINE

Application filed August 14, 1926, Serial No. 129,268, and in Hungary August 19, 1925.

My invention relates to thrashing machines and more particularly to automatic mechanisms for feeding and opening the sheaves.

If the sheaves are fed by hand, they are, as a rule, not fed properly. The thrashing drum is only able to work the grain properly if it is fed into the space between the drum and its casing in layers of uniform thickness. It is the duty of the operator to distribute the sheaves uniformly but even a skilled operator is not always able to perform this task as it is often beyond human efficiency even with normal material but cannot be performed at all with moist or entangled sheaves.

Nor do the automatic feeders as heretofore designed perform their functions properly because they are unable to adapt themselves to the varying abnormal conditions of the material. Therefore they are not an improvement over the feeding by hand, apart from their large size which is a further drawback.

Lack of uniformity in the feeding brings about unequal operation of the machine, poor thrashing and cleaning, and may even result in serious trouble.

It is an object of my invention to overcome these drawbacks and to this end I provide an opening grate at the rear of the feed opening. The grate is inclined toward the incoming material and the material is forced through its prongs by the pull of the thrashing drum. Excess material is retained and backed up on the front face of the grate. Preferably, a strickle board is provided which exerts pressure on the backed-up material so as to distribute it axially between the slats of the thrashing drum which then pull it into the feed opening. Preferably the beating slats of the thrashing drum are combined with opening and tearing slats which engage the material as it is moving axially between the slats of the thrashing drum.

In the drawings affixed to this specification and forming part thereof, two feeding and opening mechanisms are illustrated diagrammatically by way of example.

In the drawings,

Figs. 1 to 3 illustrate a device in which the grate is fixed,

Figs. 4 to 7 illustrate a modification in which the grate is carried on rocking levers.

More particularly, Fig. 1 is a sectional elevation, Fig. 2 is a plan view, partly in section of the first mechanism, Fig. 3 is a detail illustrating opening slats on the thrashing drum on a larger scale, Fig. 4 is an elevation, partly in section, of the second device, Fig. 5 is the corresponding plan view, Fig. 6 is a detail illustration showing the grate in a different position from that in Fig. 4.

Referring now to the drawings and first to Figs. 1 to 3, *p* are horizontal bars forming part of the frame of the machine, and *b* is the thrashing drum which is carried in the frame and rotated in the direction of the arrow by any suitable means, not shown. The feeding hopper is constituted by a front wall *t*₁, a rear wall *t*₂ and curved side walls *u*, *u*. *t*₃ is a flap which is hinged to the rear wall *t*₁ of the hopper at *j* and provided with a handle *d* by the operation of which the width of the opening at the base of the hopper may be adjusted, and *w* is a baffle plate at the rear wall *t*₂ which deflects grains that have been projected upwardly.

The hopper is so designed as to enable it to receive the maximum quantity of material. The curved lateral walls *u*, *u* move the sheaves toward the thrashing drum *b*. With a hopper of this construction not only the feeding operation is facilitated but perfect protection from accidents is afforded, for as compared with railings—which are often dispensed with because they are in the way when feeding—the hopper encloses the feed opening on all sides and is so high that the attendants are unable to put their hands into the hopper, much less to tumble into it. On the other hand, any obstruction to the feeding of the sheaves is removed by the considerable widening of the upper end of the hopper and the inclined faces of the hopper which conduct the sheaves directly toward the feed opening.

The opening grate *l* is secured to a transverse bar at the rear of the feed opening *e*. This bar is secured at both ends to two angular brackets *r* which are adjustably secured

on brackets *n*, also angular, and these brackets are attached to the bars *p* through the medium of a support *o* on which they may be adjusted about pivots in order to vary the angle of the grate *l*. The brackets *r* are adapted to be adjusted on the brackets *n* by means of a screwed spindle *s*₁ and are held in position on the brackets by set screws *s*.

The grate *l* is provided with prongs *a* projecting toward the drum *b*. *g*, *f* are slats on the thrashing drum which pull the material from the hopper through the opening *e* and past the prongs *a* of the grate *l* into the space between the drum and the casing *c*. The prongs *a* retain that material for which sufficient space is not provided in the opening *e* and this material is backed up in front of the prongs *a*. That portion of the sheave which is not retained by the prongs *a* is moved forward by the drum. In order to enable the drum to perform its function with sheaves of abnormal condition, that is moist sheaves, entangled sheaves or sheaves containing weed, the normal slats *g* of the drum *b* are combined with opening slats *f* on which pointed pegs *f*₁ are formed. The opening slats *f* are preferably made from spring steel and the pegs *f*₁ are formed in staggered rows by means of a chisel. The object of the slats *f* is to open the material which is pulled into the opening *e* but is retained by the prongs *a*. This material is broken and opened by the slats *f* and partly adheres to the drum which separates it from the material which remains backed up at the prongs *a*. Considerable pressure is exerted in the opening *e* and therefore the material spreads axially with respect to the drum *b*. This axially spread material enters between the slats of the drum and while moving along the slats is broken and opened by the pegs *f*₁. The outer edges of the opening slats *f* extend along a circle the radius of which is smaller than that of the circle along which the outer edges of the normal slats *g* extend. The pegs *f*₁ are staggered so that the several superimposed pegs form a series of rows at an angle to the axis of the drum *b*, as shown in Fig. 3, and this causes an increased number of pegs to act on the material in proportion to the distance to which it is forced inwards axially. Consequently, with an increase of pressure in the opening *e* the breaking and pulling action on the material is increased in proportion.

A curved strickle board *h* is adapted to slide on the prongs *a* and is displayed away from the drum *b* by the material which is backed up at the front of the prongs *a*. *i* is a link connecting the strickle board *h* with an arm *k* on a shaft *m* which is supported in the angular brackets *r*. Only one bracket *r* is visible in Fig. 2 as the corresponding bracket on the other side of the machine is concealed by the cowl which protects the mechanism. The strickle board *h* tends to return to its initial position shown in Fig. 1 by gravity so as to

follow the material which is backed up in front of the prongs *a*. The pressure which the strickle board exerts on the material may be regulated by a spring or a weighted lever *m*₂, *m*₁ on the shaft *m*, as shown in Fig. 2. In this manner the thickness of the layer which is drawn through the prongs *a*, may be regulated by adjusting the weight *m*₁ on its lever.

The arm *k* is operatively connected with an angular lever *x* which in turn is connected with the flap *t*₃ of the hopper by a link *y*. When the pressure in the feed opening *e* increases the strickle board *h* moves upwards and the lever *x* pulls the flap *t*₃ inwards so that the opening of the hopper is reduced in proportion to the increase of the pressure exerted on the strickle board.

v is a flap which is hinged to the frame at its upper end and abuts on the strickle board *h* at its lower end. The object of this flap is similar to that of the strickle board that is it also exerts downward pressure on the material by following the motion of the strickle board.

Referring now to Figs. 4 and 5 the prongs *a* and the strickle board *h* are constructed as described with reference to Figs. 1 to 3 but the prongs *a* are carried by L-shaped arms *A* at each end which are adapted to rock about pivots *B*. By these means, the strickle board is enabled to adjust itself automatically so as to vary the resistance to the inflowing material as required. The shorter ends of the L-shaped arms are suspended by springs *D* which are attached to the arms at *E*. The other ends of the springs are secured to spindles which are adapted to be adjusted by wing nuts *C*. The springs *D* tend to return the arms *A* to their initial position when they have been displaced. The arms *A* are guided by angular plates *F* arranged on the grade *l* and adapted to be adjusted by means of a spindle *L* and nuts on the spindle. Each angular plate *F* is provided with a slot *M*. Bolts *N* and nuts *O* serve for securing the plate in its position. The strickle board *h* slides on the prongs *a* of the grate *l* under the action of the link *i* and the lever *k*, and the plate *v* cooperates with the strickle board as described. The lower end of the lever *k* is pivoted to the end of the shorter part of each L-shaped lever *A* at *G* and is provided with an arm *J* which is anchored to an eye bolt *H* on the frame of the machine by a link *I*.

The operation of this modified apparatus is distinguished from that described with reference in Figs. 1 to 3 in that besides the sliding motion of the strickle board *h* on the prongs *a* a rocking motion of the entire mechanism occurs about the fixed pivot *B* as indicated in dot-and-dash lines in Fig. 4. By rocking the mechanism out of its initial position in which the longer parts of the levers *A* extend radially to the drum *b* the effective

resistance of the prongs *a* is increased when the pressure of the material in the feed opening *e* is increased. When the pressure is reduced the spring *D* pulls back the entire system into its initial position.

5 I wish it to be understood that I do not desire to be limited to the exact details of construction shown and described for obvious modifications will occur to a person skilled in the art.

10 I claim:—

1. Thrashing machine comprising a frame, a thrashing drum rotatably carried in said frame, means for supplying material to said drum, a grate arranged at an angle to horizontal at the rear of the axis of said drum and in the way of the incoming material, and a strickle board adapted to slide on said grate.

20 2. Thrashing machine comprising a frame, a thrashing drum rotatably carried in said frame, a hopper adapted to supply material to said drum, a flap hinged to the bottom of the front wall of said hopper, a grate arranged at an angle to horizontal at the rear at the axis of said drum and in the way of the incoming material, a strickle board adapted to slide on said grate, and means for operatively connecting said flap with said strickle board so as to impart rocking motion to said flap upon the reciprocation of said strickle board.

30 3. Thrashing machine comprising a frame, a thrashing drum rotatably carried in said frame, a concave in said frame, and a grate arranged at the feed opening between said drum and said concave at an obtuse angle to the tangent to the circumference at the line of intersection of the drum and grate.

40 4. Thrashing machine comprising a frame, a thrashing drum rotatably carried in said frame, slats on said drum, pegs on said slats arranged intermediate the ends of said slats and the perimeter of said drum, a concave in said frame, and a grate arranged at the feed opening between said drum and said concave at an obtuse angle to the tangent to the perimeter of said drum.

In testimony whereof I affix my signature.

ILLÉS ZAYMUSZ.
